UNITED STATES PATENT OFFICE.

MAX SCHEUER, OF NEW YORK, N. Y.

DESIGN FOR A POCKET-BOOK OR PURSE.

SPECIFICATION forming part of Design No. 22,039, dated December 6, 1892.

Application filed October 10, 1892. Serial No. 448,460. Term of patent 7 years.

To all whom it may concern:

Be it known that I, MAX SCHEUER, a citizen of the United States, residing at New York city, New York, have invented and produced 5 a new and original Design for Purses and Pocket-Books, of which the following is a specification, reference being had to the accompanying drawing, showing a perspective view of a purse provided with my design.

10 The leading feature of my design consists of a pocket-book or purse, upon the top plate of which is represented a water-fall beneath an observatory and a building, together with a railing at the side of the water-fall.

15 a represents the top plate of the purse b, surrounded by a raised rim a' on three sides.

On the fourth side the top plate is provided with a pair of overlapping stems c. Within the rim there is represented on the top plate a water-fall d beneath an observatory e and a 20 building f. At one side of the water-fall there is furthermore represented a railing g.

What I claim is—

The design for a pocket-book or purse, as herein described and shown.

MAX SCHEUER.
